FLAGMAN'S SAFETY PADDLE

Bernard D. Lamb, 4316 S. A St., Tacoma, Wash. 98408

Filed Jan. 28, 1971, Ser. No. 110,801

Term of patent 14 years

Int. Cl. D29—02

U.S. Cl. D72—1

FIG. 2

FIG. 4

FIG. 3

FIG. 1 is a front elevational view of a flagman's safety paddle showing my new design;

FIG. 2 is a side elevational view;

FIG. 3 is a rear elevational view; and

FIG. 4 is a top plan view.

The broken line disclosure in FIGS. 1 and 3 is for illustrative purposes only.

I claim:

The ornamental design for a flagman's safety paddle, as shown and described.
